UNITED STATES PATENT OFFICE.

MENNO KLAY, OF MOUNT HOPE, OHIO.

ROTARY INTERNAL-COMBUSTION ENGINE.

1,349,512.

Specification of Letters Patent. Patented Aug. 10, 1920.

Application filed October 26, 1918. Serial No. 259,779.

To all whom it may concern:

Be it known that I, MENNO KLAY, a citizen of the United States, residing at Mount Hope, in the county of Holmes and State of Ohio, have invented new and useful Improvements in Rotary Internal-Combustion Engines, of which the following is a specification.

This invention relates to rotary internal combustion engines, and one object is to provide a construction more efficient than those heretofore employed in engines of the type indicated.

A further object is to provide certain novel means for mounting a plurality of plungers, these plungers being carried in pairs by a plurality of annular members mounted in an annular chamber within a fly wheel, this annular chamber affording space for the compression of a charge between certain of the plungers carried by oppositely located rings.

A still further object is to provide in an engine of the type indicated a casing member provided with inlet and exhaust ports, a fly wheel rotatable within said casing and provided with an annular chamber, a plurality of independently mounted ring members located within the chamber, each of said ring members carrying a pair of plungers, the plungers being oppositely located, a stationary annular core carried between flanged portions of the casing and coöperating with said ring members, and means for holding one of the ring members stationary during the firing of the charge and the power stroke of the pistons carried by the other of said ring members.

With the foregoing and other objects in view, the invention consists in the novel construction, combination, and arrangement of elements hereinafter described and claimed.

In the accompanying drawings:

Figure 1 is a view in vertical section through the annular casing and showing in elevation a half section of the fly wheel, and showing also in elevation the position of the plungers mounted as described below.

Fig. 2 is a section on the line 2—2 of Fig. 1.

Fig. 3 is a section on the line 3—3 of Fig. 1.

Fig. 4 is a section on the line 4—4 of Fig. 1.

Fig. 5 is an elevation of a portion of the casing.

Fig. 6 shows a half section of the fly wheel in elevation,

Fig. 7 is a view in elevation of one of the ring members adapted to carry two of the 60 plungers,

Fig. 8 is a view in elevation of the core and showing in dotted lines the inlet and exhaust ports, near the bottom of the view,

Fig. 9 is an elevation of the outer side of 65 a half section of the fly wheel, this view being complementary to Fig. 6.

Fig. 10 is an elevation of the other ring member adapted to carry a pair of plungers, 70 this view being complementary to Fig. 7.

Fig. 11 is a detached view showing a cylindrical member and a spherical member, either one of which is employed for retaining one of the ring members while the plungers carried by the other are being 75 driven forward under the power stroke.

Fig. 12 is a detail of a cam element carried by the shaft and constituting the timing device of the ignition system.

Fig. 13 is a fragmentary view in section, 80 showing one of the elements of Fig. 11 in a position at an angle to that shown in Fig. 3. This constitutes another form, or arrangement, which may for convenience be termed a modification.

The casing comprises a plurality of members 10 and 12 each carrying a flange on its outer edge extending inwardly, these casing sections being secured together by means of bolts 14. A lower frame member 15 90 supports each casing section. The casing sections are spaced about as shown in Fig. 2 and an intermediate core 16 is secured in position by means of the bolts 14 above mentioned.

The fuel inlet 18 communicates with a port 19 in the core and shown more particularly in Fig. 1, and the exhaust 20 communicates with a port 21 in said core; a spark plug not shown is positioned within 100 the bore 22, and on the main shaft 23 is a cam 24 coöperating with a terminal 25 having connection with a lead 26 which will run to the spark plug.

A fly wheel 28 comprises a plurality of 105 similarly formed sections 29 and 30 secured together by means of bolts 31. These fly wheel sections are shown in Figs. 6 and 9, the former showing the inner face and the latter showing the outer face of each 110 section. Radially extending reinforcing ribs 41 are shown in Fig. 9 and are shown

in section in Fig. 2, portions of these ribs near the shaft 23 appearing in elevation and being designated 33. Each fly wheel section is provided with an annular channel as shown at 35, these channels together forming a chamber circular in cross section providing for the operation of the plungers, between certain of which the fuel is compressed and between others of which the explosion takes place.

10 The flanged portions of the fly wheel are spaced apart as shown in Fig. 2 and accommodate a plurality of ring members 38 and 39, these ring members carrying the 15 plungers. In Figs. 7 and 10 the ring members are shown in the position corresponding to the position of the plungers in Fig. 1. Each ring member is provided with a plurality of diametrically opposed projecting 20 members on pins 40 on which the plungers are mounted, the mounting means being shown in section in Fig. 4.

In Fig. 1 the plungers 41 and 42 are carried by one of the rings, say the ring shown 25 in Fig. 10, and designated 45. The plungers 43 and 44 of Fig. 1 are carried by the opposite ring member, say the ring shown in Fig. 7, and designated 46.

The core 16 shown in Fig. 8 is provided 30 with channels 48 and 49 of segmental form and oppositely located, each channel receiving one end of a cylindrical member with rounded ends of the form shown in Fig. 11, and designated 50, or receiving a spherical member or ball, also shown in Fig. 11 and designated 51. Each fly wheel section is provided with a plurality of recesses located diametrically opposite each other and shown in Fig. 6 where they are designated 35 53 and 54. When the plungers are in the position shown in Fig. 1, the balls or other engaging devices are also in the position shown with reference to the slots 48 and 49. At this time the ball 51 shown at the right is in engagement with recess 53 as shown in Fig. 3, and there is therefore positive connection between the rotatable ring carrying plungers 43 and 44 and the fly wheel to which the shaft 23 is keyed. This is the 40 position of the elements on the power stroke and when an explosion is taking place in the chamber 60 between the plungers 41 and 43. At this time ball 51 shown at the left engages the end of slot 48 there shown, retaining ring 45 and plungers 41, 42, against 45 reverse movement. The ball apertures through the ring members are designated 45' and 46'. The exploded gases having been exhausted through port 21 and a new 50 charge admitted through inlet 19, the plungers again assume the position shown in Fig. 1, plungers 41 and 42 advancing, with reference to the others, a distance equal to the length of channel 48.

55 When cylinder 50 engages the end of the

slot 49 of stationary core 16, it will be forced laterally through aperture 46' of ring 39 into registering aperture 53 of fly wheel member 30 (Figs. 6 and 7). In Fig. 1 element 50 is dotted in slot 49 it having in fact just passed from the slot into the position shown in Fig. 3, for engagement with the fly wheel during the power stroke.

At this time the cylinder 50 in aperture 45' is opposite slot 48 of stationary core 75 16 and is forced into the slot, there being at this moment no registering aperture in the fly wheel. Ring member 38 and the plungers mounted thereon are therefore held against reverse movement, while the power 80 stroke is being delivered, by the engagement between element 50 and the adjacent end of slot 48.

In that form of the device shown in Fig. 13 the element 50 is positioned at a different 85 angle with reference to the axis of rotation.

What is claimed is:

1. In a device of the class described, a casing, a fly wheel mounted therein and including an annular chamber, a plurality of ring members spaced apart and located within said chamber, a plurality of plungers carried by each ring member, the plungers on each ring being located diametrically opposite each other, means for introducing an explosive fluid between certain of said plungers and means for effecting the exhaust of the exploded gases, a stationary element, a device movable through one of the ring members for connecting the latter and the fly wheel, at a given time, and a device movable through the other ring member for connecting the member last named with the stationary element, said stationary element 90 being interposed between the rings. 95

2. In a device of the class described, a casing, a fly wheel mounted therein and including a circumferential chamber, a plurality of ring members within said chamber, a plurality of plungers carried by each ring member, the plungers operating within the aforesaid chamber, a stationary core, portions of which extend between the ring members, and means for retaining one of the ring members and the plungers thereon stationary while the other of said ring members is transmitting the power stroke to the fly wheel. 110 115

3. In a device of the class described, a casing, a fly wheel operating therein, a shaft extending through the casing and mounting said fly wheel, the fly wheel including a plurality of oppositely located sections, each of which is provided with an annular channel, the channels together forming a compression and combustion chamber for the engine, a plurality of ring members rotatable with reference to the casing, a core comprising an annular member 120 125 130

located between the ring members and rigidly mounted with reference to the casing, a plurality of plungers carried by each ring member, the plungers of a given ring member being located diametrically opposite each other, and means for retaining one of the ring members in a fixed position with reference to the core, while the other of said ring members and the plungers carried thereby are delivering the power stroke to the fly wheel.

4. In a device of the class described, a casing, a rotatable member mounted therein and providing a circumferential compression and combustion chamber, a plurality of

plungers, means for independently mounting the plungers in pairs for operation within said chamber, a core comprising an annular member located between the mounting means for the plungers, said core being provided with segmentally formed slots and said rotary member being provided with recesses, and means operating within the slots and adapted at times to engage the recesses for retaining certain of said plungers in a stationary position while the remaining plungers are delivering the power stroke to the fly wheel.

In testimony whereof I affix my signature.
MENNO KLAY.
